United States Patent Office

Des. 210,577

Patented Mar. 26, 1968

210,577

BUILDING

Ray C. Bender, P.O. Box 5265,
Pittsburgh, Pa. 15206

Filed May 2, 1966, Ser. No. 2,103

Term of patent 14 years

(Cl. D13—1)

Fig. 1.

Fig. 2.

FIGURE 1 is an isometric view of a building according to my invention, each isometric corner view corresponding to FIGURE 1 being identical except for the omission of the staircase, and

FIGURE 2 is a top plan view of the building of FIGURE 1.

The ground platform is shown in broken lines in FIGURE 1 for illustrative purposes only.

I claim:

The ornamental design for a building, as shown and described.
